UNITED STATES PATENT OFFICE.

RUDOLPH W. GLASNER AND OLOF G. NILSON, OF CHICAGO, ILLINOIS, ASSIGNEES TO MARQUETTE TOOL & MANUFACTURING COMPANY, OF CHICAGO, ILLINOIS, A CORPORATION OF ILLINOIS.

BLANK-HOLDING MEANS.

Application filed October 21, 1922. Serial No. 595,985.

This invention relates to improvements in blank holding means particularly adapted though not necessarily limited in its use with sheet metal presses.

5 Heretofore with sheet metal presses it has been customary to provide a pressure cushion operating upon the blank holding means and with such cushion and during the operation of the press the ram or movable 10 member not only operates upon the work to form the same, but also must work in opposition to the pressure of the blank holding means, with the result that among other things more power is required to operate the 15 press.

In order to overcome these objections and to increase the capacity of the press without increasing its size or power necessary for its operation, and to provide improved 20 means whereby the blank holding means and the ram or movable member of the press may operate independently of each other so that it is not necessary for the ram or movable member to operate in opposition to the 25 stress of the blank holding means, is one of the objects of the present invention.

A further object is to provide an improved blank holding means embodying pressure creating means for actuating the 30 blank holder and means whereby the said pressure will at a predetermined point in the operation of the machine also operate upon the movable part of the press for assisting the said movable part in its operation.

35 A further object is to provide an improved device of this character which will be simple, durable, cheap and compact in construction, and effective and efficient in operation, and which may be readily applied to sheet metal presses and which may as readily be detached therefrom without altering the construction or interfering with the original purpose for which the machine 40 was designed.

To the attainment of these ends and the accomplishment of other new and useful objects as will appear, the invention consists in the features of novelty in substantially the construction, combination and arrangement of the several parts hereinafter more fully described and claimed and shown

in the accompanying drawings illustrating this invention and in which—

Figure 1 is a view partly in elevation and 55 partly in section of a portion of a sheet metal press, having a blank holding means applied thereto and constructed in accordance with the principles of this invention. 60

Figure 2 is a diagrammatic view showing the method of applying a plurality of 65 cushions to a press.

Figure 3 is a view similar to Figure 1 of a modified form of the invention. 65

Referring more particularly to the drawing the numeral 10 designates a stationary portion of a mechanically operated sheet metal press, 11 is the lower blank holder, and 12 a movable part or the ram of the 70 press carrying the die punch 13, all of the ordinary and well known construction.

The ram 12 is adapted for a reciprocating movement toward and away from the die member 11. 75

The numeral 14 designates a blank holder ring and 15 a blank holder which co-operate with the die member 11 for gripping the material 16 therebetween and for holding the same during the operation of the punch 13 80 upon the material.

A fluid pressure cushion embodying a cylinder 17, telescoping with a cylinder 18 is provided for controlling the operation of the blank holder 15. 85

Any number of these fluid pressure cushions may be employed and as the construction and operation of each cushion is the same, the description of one will apply 90 equally as well to them all.

The cushion is supported in any desired or suitable manner from a stationary portion of the press and a simple and efficient means and as shown in the present invention, embodies a rod or projection 19 which 95 is connected with the cylinder 18 to project therebeyond and this rod is anchored or secured to the fixed member 10 of the press in any suitable manner preferably by inserting one end 20 of the rod into the member 100 10 and securing the same by means of a suitable fastening screw or bolt 21.

Carried by the rod 19 is a piston 22 which operates in the cylinder 17 and there is pro-

vided a passage 23 in the rod 19 within the cylinder which passes through the end thereof and forms a communication between the cylinder 17 and the cylinder 18.

5 Interposed between the cylinders 17 and 18 is a piston member 24 which is preferably connected and forms the end of the cylinder 17, and through which piston 24 the piston rod 25 is adapted to slide, there being 10 provided a suitable stuffing box 26, to form a fluid tight joint between the two.

If desired, there may be provided an outlet passage 27 leading from the inside of the cylinder 17 between the pistons 22 and 15 24 and which passage 27 discharges to the atmosphere.

Connected with the cylinder 17, preferably to the end 28 thereof, is a depending rod 29, which passes loosely through a portion 20 of the ram 12. This rod 29 may be of any desired length and is connected in any desired or suitable manner with the draw ring 14, such as by means of a fastening screw or bolt 30, so that when the cylinder 17 moves with relation to the cylinder 18, the draw ring 14 and the blank holder 15 will move independently with respect to the movement of the ram 12.

Fluid pressure is supplied to the cylinder 30 17 from any suitable source and in any suitable manner preferably by means of an inlet pipe 31, which discharges into the cylinder 17 and receives its supply through a pipe or connection 32, which latter in turn leads 35 from the source of supply.

A suitable valve 33 is provided for controlling communication between the pipes 32 and 31 and this valve is preferably arranged within a casing 34, having a discharge outlet 40 35, leading to the atmosphere.

The valve 33 is provided with a passage-way 36, so arranged that when the valve is in the position shown in Figure 1, communication will be established between the pipe 45 32 and the pipe 31 for the purpose of delivering fluid pressure into the cylinder 17. The valve 33, however, may be adjusted so as to close communication between the pipe 32 and establish communication between the 50 pipe 31 and the pipe 35, so that the fluid from the cylinder 17 may be discharged through the pipe 35 and led to any suitable point.

With this construction it will be manifest 55 that when fluid pressure is admitted into the cylinder 17, the fluid will also flow through the opening 23 and into the cylinder 18 to establish the same relative pressure in the two cylinders.

In order to release or relieve the pressure or stress of the draw ring 14 and blank holder 15 upon the work or blank 16, it is only necessary to relieve the pressure in the cylinders 17-18, which may be accomplished in any suitable manner and in the

present invention a simple and efficient means for accomplishing this result is shown as embodying the valve 33, which may be adjusted so as to establish communication between the pipes 31 and 35.

The valve 33 may be operated in any desired or suitable manner such as by means of a handle 36, with which is connected a suitable operating rod 37, adapted to be actuated in any desired manner.

If desired, a suitable regulating valve indicated diagrammatically at 38, may be provided in the pipe line 32, and which pipe line leads from any suitable source of pressure supply to the cylinders 17 and 18.

It is thought that the operation of this invention will be clearly understood from the foregoing, but briefly stated it is as follows. When the press is not operating the ram 12 will be elevated and the cylinder 17 85 will be telescoped within the cylinder 18.

Assuming that fluid pressure is admitted to the cylinders 17-18 and the ram starts to descend, the fluid pressure in the cylinders 17 and 18 together with the weight of the draw ring 14 and blank holder 15 will cause the latter to descend with the ram, the rods 29 being of such a length that the draw ring 14 and blank holder 15 will be in a position 90 that the blank holder 15 will engage the work 16 ahead of the punch 13 so that the fluid pressure in the cushions will operate upon the ram 12 to assist in lowering the ram, and at the same time the fluid pressure in the cylinders will operate upon the blank 100 holder 15 to cause the latter to grip the work 16.

Inasmuch as the blank holder 15 engages the work before the punch 13 engages the work it will be manifest that the stress of the cushion operates directly upon the blank holder 15 so that from the time that the blank holder 15 engages the work the pressure of the cushion will be directly upon the blank holder and the ram will be relieved 105 of such pressure. In other words as soon as the blank holder 15 engages the work the movement of the blank holder will be arrested but the ram will continue to move independently of the blank holder and no 110 power is necessary from the ram to hold the work, the work being held entirely by the pressure exerted upon the blank holder by the stress of the blank holding means.

After the forming operation, the ram first 115 starts to ascend for a predetermined portion of its travel and at a further predetermined point in the operation of the machine the pressure within the cylinders 17 and 18 is relieved and the blank holder will ascend with 120 the ram.

Obviously the pressure in the cylinders 17-18 may be regulated by the pressure regulating means 38, and it will be manifest 125 that with this improved invention it is pos-

sible to control the pressure or stress of the blank holding means at any point in the operation of the machine.

It will be manifest that any number of these pressure creating means may be provided for operating upon the blank holder according to the work to be performed and in the diagrammatic illustration shown in Figure 2, means are provided for employing four sets of cylinders, but it is obvious, as before stated, any number of cylinders may be employed.

In the diagrammatic illustration shown in Figure 2, one of the valves 33 is provided for each cushion element and these valves are adapted to be independently operated so as to control the pressure in each element independently of the other and if desired, regulating valves 38 may also be provided in the pipe line connections and which regulating valves are individual to the cushion elements so that a different degree of fluid pressure may, if desired, be exerted in the individual cushion elements.

If the fluid pressure blank holding means embodies only one cushion element or if it is desired to simultaneously control a plurality of these cushion elements a single controlling valve 39 may be provided in the pipe line connection, and which valve 39 may be of a similar construction to the valve 33, one portion of the valve controlling the fluid inlet pipe 40, leading to the cushion elements and corresponding with the pipe connection 32, and the said valve is also provided with a discharge outlet 41, corresponding with the outlet 35 and communicating with the atmosphere.

Thus it will be seen that by setting the valve 39 so as to establish communication between the source of fluid supply and the pipe lines 42, which correspond with the pipe line 32, the fluid pressure in all of the cushions may be simultaneously controlled, provided, however, that the valves 33 are first opened for a simultaneous control.

When it is desired for an individual control then the valves 33 of the respective cushion elements are operated as desired.

A regulating valve 43 may also be provided in the pipe connection 40 and corresponds with the regulating valve 38, shown in Figure 1.

In Figure 3 of the drawings, there is shown another adaptation of the blank holding means and in this form of the invention the cylinder 44 is anchored to the ram or movable part 12 of the press and leading through the bottom of the cylinder is an outlet 45, which communicates with the atmosphere.

The cylinder 46 which telescopes with the cylinder 44 is supported in any suitable manner from a stationary part of the machine such as the part 10 by means of a de-

pending rod 47, which passes through the head 48 of the cylinder 46, and also passes through a suitable opening in the head 49 of the cylinder 44, and which latter head forms a piston. Suitable packing 50 is arranged within the opening in the head 49 through which the portion 51 of the rod 47 reciprocates.

An opening 52 is provided through the portion 51 of the rod 47, which has communication as at 53 with the cylinder 44 and also has communication as at 54 with the pipe connection 55. The passage 52 communicates with the cylinder 46 by means of a suitable opening 56 and a suitable controlling valve 57 has connection with the pipe 55. The valve 57 may be operated in any suitable manner such as by means of a handle 58 to which handle may be connected an operating rod 59, and which rod may be connected, if desired, with any movable part of the machine.

Leading from the valve 57 is a pipe connection 60, which connects with any suitable source of pressure supply and if desired there may be arranged in the pipe connection a suitable regulating valve 61.

With this form of the invention the operation briefly stated is as follows. Assuming the ram 12 to be elevated the blank holder ring 14 and the blank holder 15 will also be elevated. Pressure may be admitted to the cylinders 44-46 at any time during the operation of the machine that it is desired or before the machine commences to operate. As the ram descends the cylinder 44, which is secured to the ram, will also descend and during this descending movement the fluid pressure in the cylinder 46 operating on the piston 49, will exert its stress upon the ram to assist in its descending operation.

As soon as the blank holder 15 engages the work 16, the movement of the blank holder will be arrested and the blank holder will be held in a gripping position upon the work 16 by means of the fluid pressure exerted in the cylinder 44. The blank holder engages the work in advance of the die punch 13, and the pressure will be even in the cylinders 44 and 46. When the blank holder is arrested the ram 12 continues in its downward movement by press operating means and just at the time that the blank holder is arrested the pressure in the cylinders 44 and 46 will continue to operate upon the ram 12 to assist in forcing the ram downward.

When the blank holder 15 is in engagement with the work 16 and is arrested in its downward movement, the piston 62 in the cylinder 44, and which piston is connected with the rod 19, will be arrested in its movement and the bottom of the cylinder 44 will move away from the piston. Inasmuch as

the portion 51 of the rod 47 is stationary and projects into the cylinder 46 and also into the cylinder 44, the end of the portion 51 will telescope into the opening 63 in the 5 rod 19.

It will therefore be manifest with this improved invention the fluid pressure is first exerted upon the blank holding means and when the blank holding means has been arrested in its movement and is gripping the work, the ram still operating under the influence of the pressure in the cushioning device will also descend and be arrested in its 10 operation of forming the material.

15 During the relative movement of the piston 62 and cylinder 44, it will be manifest that atmospheric air will be first drawn into the cylinder 44 beneath the piston 62, and then discharged therefrom through the 20 opening 45.

It will be manifest from the foregoing that by reason of power being added to the ram during its downward movement, when the work is to be performed, by the stress 25 of the blank holding means upon the machine, the capacity of the press will be greatly increased without making it necessary to increase the power for the operation of the press.

30 While the preferred form of the invention has been herein shown and described it is to be understood that various changes may be made in the details of construction and in the combination and arrangement of the 35 several parts, within the scope of the claims, without departing from the spirit of this invention.

By the term "mechanically operated" as used in the claims it is to be understood to 40 mean a press which is operated in the ordinary and well known manner by means of the usual rotary crank.

While there has been shown and described 45 a simple and efficient means for accomplishing the results desired it is to be understood that the drawings herewith submitted are only illustrative of the principle and therefore, it is desired that the drawings herewith submitted shall be considered as being 50 merely diagrammatic.

What is claimed as new is:

1. A mechanically operated draw press 55 embodying a forming block, a movable element co-operating with the forming block, and yielding blank holding means movable with and with respect to the said element, whereby said movable element will be operable upon the work and will be relieved of the stress of the said blank holding means, the said blank holding means embodying a plurality of yieldable cushion elements, the said cushion elements being disposed above, the work.

60 2. A mechanically operated draw press 65 embodying a forming block, a movable ele-

ment co-operating with the forming block, and yielding blank holding means movable with and with respect to said element, whereby said movable element will be operable upon the work and will be relieved of the stress of the said blank holding means, the said blank holding means embodying a plurality of fluid pressure cushion elements, the said fluid pressure cushion being disposed above the work.

75 3. A draw press embodying a forming block, a movable element co-operating with the forming block, yielding blank holding means, said movable element being operable upon the work in such a manner that it will be relieved of the stress of the said blank holding means, the said blank holding means embodying a plurality of fluid pressure cushion elements, and means for controlling the said fluid pressure.

80 4. A draw press embodying a forming block, a movable element co-operating with the forming block, yielding blank holding means, said movable element being operable upon the work in such a manner that it will be relieved of the stress of the said blank holding means, the said blank holding means embodying a plurality of fluid pressure cushion elements, and means individual to the said elements for independently 85 controlling the said pressure.

90 5. A draw press embodying a forming block, a movable element co-operating with the forming block, yielding blank holding means, said movable element being operable upon the work in such a manner that it will be relieved of the stress of the said blank holding means, the said blank holding means embodying a plurality of fluid pressure cushion elements, and means common 95 to the said elements for simultaneously controlling the said pressure.

100 6. A draw press including a forming block, a movable element co-operating with the forming block, yielding blank holding 105 means, said movable element being operable upon the work in such a manner that it will be relieved of the stress of the said blank holding means, the said blank holding means embodying a fluid pressure element, and means for controlling the said fluid pressure.

110 7. A draw press including a forming block, a movable element co-operating with the forming block, yielding blank holding 115 means, said movable element being operable upon the work in such a manner that it will be relieved of the stress of the said blank holding means, the said blank holding means embodying a fluid pressure cushion element, and means for controlling the said fluid pressure, the said fluid pressure cushion being disposed above the work.

120 8. In combination, a sheet metal forming die, said die including male and female 125

forming members and blank holding members, one of the members of the die being actuated by a mechanical power means, and a fluid pressure cushion actuating the other member of the die.

9. In combination, a sheet metal forming die, said die including male and female forming members and blank holding members, one of the members of the die being actuated by a mechanical power means, and a fluid pressure cushion actuating the other member of the die, the said cushion being mounted above the work.

10. In combination, a sheet metal forming die, said die including male and female forming members and blank holding members, one of the members of the die being actuated by a mechanical power means, and a fluid pressure cushion actuating the other member of the die, the said cushion oper-

ating to relieve the power driven members of the die of stress in addition to the driving stress thereof.

11. In combination, a sheet metal forming die, said die including a male and female forming members and blank holding members, one of the members of the die being actuated by a mechanical power means, and a fluid pressure cushion actuating the other member of the die, the said cushion being mounted above the work and operating to relieve the power driven members of the die of stress in addition to the driving stress thereof.

In testimony whereof we have signed our names to this specification, on this 19th day of October, A. D. 1922.

RUDOLPH W. GLASNER.
OLOF G. NILSON.
